(57) **CLAIM**

The ornamental design for a shoe, as shown and described.

DESCRIPTION

FIG. 1 is a bottom view of a shoe showing our new design; and,

FIG. 2 is a perspective view thereof.

The broken lines in the figures and the lightened area(s) within the broken lines show portions of the shoe that form no part of the claimed design.

1 Claim, 2 Drawing Sheets

FIG. 1

FIG. 2

UNITED STATES PATENT AND TRADEMARK OFFICE
CERTIFICATE OF CORRECTION

PATENT NO. : D1,000,789 S
APPLICATION NO. : 29/803604
DATED : October 10, 2023
INVENTOR(S) : Falk Bruns and Neale Barnes

Page 1 of 1

It is certified that error appears in the above-identified patent and that said Letters Patent is hereby corrected as shown below:

On the Title Page

In Item (63), please add --now Pat. No. Des. 989,446--.

Signed and Sealed this
Twenty-eighth Day of May, 2024
Katherine Kelly Vidal
